FIG. 6.

UNITED STATES PATENT OFFICE.

GEORGE B. DRACH, OF JERSEY CITY, NEW JERSEY, ASSIGNOR TO JERSEY CITY PRINTING COMPANY, OF JERSEY CITY, NEW JERSEY, A CORPORATION OF NEW JERSEY.

METHOD OF DRILLING BOOKS.

1,273,468.

Specification of Letters Patent.

Patented July 23, 1918.

Application filed January 16, 1917. Serial No. 142,627.

To all whom it may concern:

Be it known that I, GEORGE B. DRACH, a citizen of the United States, residing in the city of Jersey City, in the county of Hudson and State of New Jersey, have invented 5 certain new and useful Improvements in Methods of Drilling Books; and I do hereby declare that the following is a full, clear, and exact description thereof, which, in connection with the drawings forming a part 10 of this specification, will enable others skilled in the art to which my invention relates to make, use, and practise the same.

My invention relates generally to a method 15 of drilling books by transversely piercing particularly paper-covered books such as telephone directories and the like, to which a hanger cord is to be attached by insertion through a corner thereof.

20 The object of my invention is to accomplish the boring or drilling of books economically and at high speed at relatively the same point in each and so that the hole produced shall be uniform not only 25 throughout the book but also at the outer sides, and particularly at the side where the drill leaves the book in piercing it, so that splitting or tearing of the paper about the edge of the bore may be avoided, and 30 the cover or case be not marred or defaced.

In drilling books it has heretofore been customary to employ as an anvil a female die in which the drill enters. The use of such die has presented the difficulty that it 35 soon becomes burred. Ordinarily, after a few hundred books have been drilled, the die is so drill-marred that it causes a rough hole to be formed at the point of exit of the drill. My method essentially consists, in 40 effect, in the provision of a new female die member for each stroke of the drill. This is attainable by drilling a series of books at the same stroke of the piercing tool but checking such drill before it has completely 45 penetrated the last member of the series, then withdrawing the drill, removing the pierced books, transposing the partially drilled book constituting the last member of the series to become the first member of 50 the succeeding series, and repeating the steps in the operation. By locating the partially pierced book as the first member of the succeeding series, the advantage is secured that its cover is not marred by the advancing and

entering drill because it has been previously 55 pierced. The transposed book may also serve as a pattern by which the accuracy of direction of the tool may be observed, but this function is of relatively minor importance, since the drill reciprocates in a fixed 60 path. The principal feature of advantage and utility characterizing my method resides in the avoidance of injury to the last member of the series, the result attained by the herein described method. 65

The novel features of construction and operation of a drilling machine well adapted to my method will hereinafter be fully described, together with the best form thereof 70 now known to me for attaining the particular features of novelty and utility characterizing my invention and which means constitute the subject-matter of my companion application Serial Number 166,336, filed May 4, 1917, as a division hereof. 75

In the accompanying drawings, Figure 1 is a side elevation of the machine; Fig. 2 is a plan view; Fig. 3 is a detailed view showing adjusting means adapted for feeding books of different thickness from those shown in 80 Figs. 1 and 2; Fig. 4 is a fragmentary plan view of the means for feeding books of the thickness for which the adjustment shown in Fig. 3 is adapted; Fig. 5 is an end view of the machine; Fig. 6 is a plan view of a 85 portion of the machine showing the parts in a different position from that shown in Fig. 2; Fig. 7 is a diagram representing the cycle of operations of the machine.

Referring to the drawings in detail, a 90 driving shaft 1 is journaled in bearings 2 forming part of the main frame 3. Secured to the driving shaft is a worm 4 in mesh with a worm wheel 5 which is secured to a shaft 6. Secured to shaft 6 is a cam 7 having a cam groove 8 in which travels a roller 9 journaled on the bar 10. One end of the bar 10 is provided with a slot 11 so that it will ride on the shaft 6. The other end of the bar 10 is connected to an arm 12 which is secured to a shaft 13. Secured to shaft 13 is an arm 14 having rollers 15 journaled on its outer end. Rollers 15 travel in an annular groove 16 formed in a collar 17 which is secured to a rod 18. To one end 100 of rod 18 is attached a drill 19. The rod 18 is provided with a slot 20 which is engaged by pins 21 projecting inwardly from

a sleeve 22, which surrounds the rod 18. The end of the sleeve 22 is provided with portions 23 of smaller diameter, which are free to rotate in bearings 24. Forming part 5 of sleeve 22 is a helical spur pinion 25 meshing with the helical spur gear teeth 26 formed on a wheel 27 which is secured to the driving shaft 1. Secured to shaft 6 is a wheel 28 which is provided with a cam 10 groove 29, in which travels a roller 30 journaled on a bar 31. One end of bar 31 is provided with a slot 32 so that it will ride on the shaft 6. The other end of the bar 31 is connected to an arm 33 which is secured 15 to a shaft 34. Secured to shaft 34 is an arm 35 which is connected by a link 36 to a plunger 37 having a reciprocating movement in guides 38. Pivoted on the plunger 37 is a pawl 39 adapted for engagement with 20 teeth 40 of a ratchet wheel which is secured to a shaft 41. To shaft 41 are secured chain-wheels 42 (see Fig. 2) over which travel chains 43 traveling over chain-wheels 44 which are secured to a shaft 45. The chains 25 43 travel at a slightly higher level than the upper side of a table 46, so that when a group of books 47 are transferred from a trimming machine and placed upon the table 46, such of the group as rest upon the 30 chains will be supported by the chains and not by the table. The books resting upon the chains pass between side guides 48 and a side guide 49 located at a height greater than the guides 48. The action of the part 35 *f* or cam groove 29 on roller 30 of bar 31 and parts connected therewith causes the forward movement of the plunger 37 and the consequent movement of the chains 43, thereby causing the forward movement of 40 the books 47. The forward movement of the books causes one of said books *d* and the plunger 37 to press the preceding books *c* and *b* forward between guides 50 and 51 forming part of a channel which is shifted 45 laterally from the channel formed by guides 48. At the end of the forward movement of the plunger 37 the book *b* is forced against an anvil 52 through which passes the drill 19 attached to the rod 18. During the time that the part *g* of cam groove 29 causes the plunger 37 to clamp the books *c* and *b* against the anvil 52, the part *h* of cam groove 8, as shown in Figs. 1 and 7, will cause forward movement of the drill 19, thereby causing a hole 53 to be drilled 50 through book *b*, and a hole 54 to be drilled halfway through the book *c*. During the time the part *i* of cam groove 8 causes return movement of the drill 19, the part *j* of cam groove 29 will cause return movement 55 of the plunger 37, thereby causing the books *c* and *b* to be released. Secured to the shaft 6 is a wheel 55 having a cam groove 56 in which travels a roller 57 journaled on a lever 58 60 which is pivoted at 59. The free end of

lever 58 is connected by a link 60 to one end of a lever 61 which is pivoted at 62. The other end of lever 61 is connected to a plunger 63 which is connected to an arm 64 pivoted at 65. Lever 58 is also connected 70 by a link 66 to one end of a lever 67 which is pivoted at 68. The other end of lever 67 is connected to a bar 69 which is connected to an arm 70 pivoted at 71. Pivoted to the bar 69 is a pivoted plunger 72. The plunger 72 is provided with an arm 73 which is connected to the bar 69 by means of a spring 74. During the time that part *k* of cam groove 8 causes the drill 19 to remain in the back position, the part *l* of cam groove 56 80 acting on roller 57 of lever 58 and parts connected thereto, causes movement of the plungers 63 and 72 from the position shown in Fig. 2 to the position shown in Fig. 6. The movement of plunger 63 causes the book *b* to be moved against an inclined guide 75 which serves to force one end of the book slightly forward, the book at the end of movement of the plunger 63 being in alignment with a channel formed by side guides 90 76 and 77, the movement of the plunger 72 at the same time causing the outer end of the plunger to be moved behind the book *d* succeeding the book *c*. The part *M* of cam groove 56 will then cause return movement 95 of the plungers 63 and 72, whereby the plunger 63 is moved clear of the book *c*, and plunger 72 forces book *d* over against an incline 78 forming part of the side guides 49 and 51, whereby one end of the book is 100 moved slightly forward. At the end of movement of the plunger 72, the book *d* will be moved into range with the channel formed by the side guides 50 and 51 and to rest in front of the plunger 37. Then as 105 the part *f* of cam groove 29 causes movement of the plunger, the book *d* and book *c* will be forced forward against the anvil 52 in a manner similar to that previously described with reference to the forward movement of the books *c* and *b*. At the same time movement of the books *d* and *c* will cause movement of the book *b* forward between the guides 76 and 77. The book *b* will then occupy the position shown by book 110 *a* in Fig. 2. When forward movement of the plunger 37 by means of pawl 39 causes rotation of the shaft 41, a chain wheel 79 secured to the shaft 41 causes movement of a chain 80 traveling over a chain wheel 81 120 which is secured to a shaft 82. Secured to shaft 82 are chain wheels 83, over which travel chains 84 traveling over chain wheels 85 which are secured to a shaft 86. During the lateral movement of the books *c* and *b* they are supported by the table 46 and not by the chains 43 or chains 84, but when the books are moved to the position shown by book *a*, they travel up onto the chains 84 125 which are placed at a higher level than the 130

table 46. As shown in Figs. 1, 2 and 6, the machine is adjusted for feeding and boring thick books.

By reference to Fig. 2 it will be seen that 5 the hole that has been drilled extends entirely through one book and part way through a second book. When the plunger 63 moves the book *b* away from the anvil 52, and the plunger 37 causes the book *c* to 10 be moved up against the anvil, it will be seen that the hole 54 extending part way through the book is then forced against the anvil so that as the drill is fed forward the book, being partly drilled before the drill 15 enters the book, the cover of the book will not be marred by the drill. When it is desired to feed and bore thin books, the adjustments shown in Figs. 3 and 4 are made, so that the drill when moved forward, will 20 drill through two thin books and part way through a third thin book. The space occupied by the three books shown in Fig. 4 is greater than that occupied by the two books shown in Fig. 2. Therefore, the plunger 37 25 must have a longer stroke, which is accomplished by disconnecting the bar 31 from the arm 33 and connecting it to an arm 87 which is secured to the shaft 34, whereby space is provided for two thin books to be moved 30 between the incline 78 of the guide 49 and a thin book having the hole 54 bored part way through. The guide 49 is also adjustable to provide for more space, the adjustment being accomplished by releasing clamping 35 bolts 88 passing through a slot 89 formed in the side guide 51 of which the guide 49 forms a part, the guide 49 being secured in place by means of the clamping bolts 88.

Having thus described my invention, and 40 shown the preferred structural embodiment for practicing same, which means may be materially varied without departing from the essential features of my disclosure, and without limiting my invention to the par-

ticular means illustrated and set forth except as required by the scope of the appended claims, I claim as new:

1. The method of drilling books consisting in presenting to the piercing tool a plurality of books, causing all preceding the last to be completely pierced and the last to be partially pierced by the same stroke of the tool, removing those completely pierced and advancing the partially pierced book to the position next the drill, placing others behind it, and repeating the operation, whereby the last unit of the series constitutes an anvil, is then advanced to become the first unit of the next series, and then constitutes a shield for the first member of the succeeding series.

2. The method of uniformly drilling a series of groups of books, consisting in employing one of said group as an anvil while piercing a plurality of books preceding it, and then repeating the step, using the anvil book as the first member of the succeeding group.

3. The method of simultaneously drilling a plurality of books consisting in presenting a series of books to a piercing tool, completely piercing all but the last and partly piercing the last, at a single stroke; advancing the partially pierced book next to the tool, and using same as a shield and guide for a second series of books positioned behind it.

4. The method of protecting books while being drilled consisting in interposing said books between a pair of books, each of which pair is partially drilled by the same stroke.

5. The method of protecting books while being drilled consisting in clamping a plurality of said books between two others, one of which two is previously partially drilled and the other of which two is partially drilled by the same stroke as the others.

GEORGE B. DRACH.
